UNITED STATES PATENT OFFICE

2,491,844

CAN OPENER

Lorenz E. Wurtzebach, Denver, Colo.

Application August 26, 1946, Serial No. 692,958

2 Claims. (Cl. 30—8)

1

The invention relates to can openers and has for its object to provide a device of this kind, comprising a body member adapted to be attached to a support, and provided with a can feeding wheel for feeding and rotating the can against one of a plurality of can piercing and cutting members carried by a finger member pivotally mounted on the body member.

A further object is to mount the multiple blade element on the finger engaging member, and to provide the cutting member with a plurality of apertures, any one of which is adapted to receive a holding pin on the finger engaging member for properly positioning and holding any of the cutting members in operative position in relation to the can feed wheel.

A further object is to provide the body member with a yoke arching the lower portion of the cutting element and forming a downward limiting stop for the finger engaging member.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a side elevation of the can opener, showing the parts in operative position.

Figure 2 is an enlarged side elevation of the outer end of the opening, showing the cutting element raised, preparatory to the insertion of the can.

Figure 3 is a vertical transverse sectional view taken on line 3—3 of Figure 1.

Figure 4 is a vertical transverse sectional view taken on line 4—4 of Figure 1.

Figure 5 is a detail perspective view of the finger engaging member.

Referring to the drawing, the numeral 1 designates a supporting plate, secured to a vertical support by means of screws 2. The outer face of the plate 1 is off-set and is provided with an off-set vertical lug 3, which lug overlies the lateral flange 4 carried by the body 5. Body 5 is also provided with an oppositely extending flange 6, having a vertical slot 7 therein for the reception of a securing bolt 8, therefore it will be seen that the body is rigidly held on the plate 1 and against pivotal action.

Rotatably mounted in the outer lower end of the body 5 is a feed wheel shaft 9, having a feed wheel 10 on one end of the shaft and a handle

2

11 on the other end, so the feed wheel can be rotated for feeding and rotating the can when in position in the device, and at the same time supporting the can. Pivotally mounted at 12 to the body member 5 is a finger engaging lever 13, which lever is adapted to be swung downwardly for forcing one of the cutting points 14 of the multiple cutter 15 into the can.

Referring to the Figure 3, the multiple cutter 15 passes downwardly through the brace yoke 16 into the can, and it will also be noted that the downward movement of the member 13 is limited by engagement thereof at 17 with the yoke 16. In operation, the bead of the can is placed over the feed wheel 10 when the finger engaging member 13 is in raised position, as shown in Figure 2, then the operator, with his left hand, forces the finger engaging member 13 downwardly until the point 14 pierces the can, and then the lever 11 is rotated in the direction of the arrow a, and the can will be fed and rotated by the feed wheel 10 and simultaneously cut out on its upper end.

The multiple cutter 15 is held on the finger engaging member by a screw 18, and in turn held against rotation on the finger engaging member by the holding pin 19, carried by the member 13, and which pin is received in one of the apertures 20 in the cutter. By providing a multiple cutter, it is obvious when one becomes damaged or dulled, a fresh cutter may be easily and quickly positioned in down position, thereby obviating the difficulty now experienced with devices of this kind.

It will be noted that each arm of the multiple cutter is so shaped, that when in down position its cutting edges inclined upwardly and outwardly for a cutting and shearing operation, and also by providing this particular angle there will not be a tendency for the finger engaging member 13 to be forced up during the can cutting operation.

From the above it will be seen that a multiple blade can opener is provided which is simple in construction and one having the multiple advantages set forth. The under side of the body 5 is provided with a bottle cap remover 21, formed by one of the reinforcing flanges 22.

The invention having been set forth what is claimed as new and useful is:

1. A can opener comprising a supporting plate, a can feed wheel adjacent the lower side of said plate, a cutter carrying lever pivoted to the plate above the wheel intermediate the inner end of the plate and the axis of the feed wheel, a cutter

mounted on said cutter lever and adapted to be swung downwardly to a cutting position above the feed wheel, said cutter having a screw connection to the cutter lever and a lug carried by the cutter lever and extending into an aperture 5 of the cutter.

2. A device as set forth in claim 1 including a U-shaped yoke carried by the plate above the feed wheel and adapted to arch the cutter, said yoke cooperating with the lever when in operative position for limiting the downward movement of the cutter lever. 10
